CLAIM

The ornamental design for an infrared therapy lamp, as shown and described.

DESCRIPTION

FIG. 1 is a front, right and top perspective view of an infrared therapy lamp, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion 9 shown in FIG. 1;

FIG. 10 is an enlarged view of portion 10 shown in FIG. 1;

FIG. 11 is a front, right and top perspective view of the pole and the head of the infrared therapy lamp in a retracted and rotated state; and,

FIG. 12 is a front, right and top perspective view of the pole of the infrared therapy lamp in a curved state.

The dash dot dash lines in FIGS. 1, 9 and 10 are for the purpose of depicting the boundary lines of the enlarged views and form no part of the claimed design.

1 Claim, 12 Drawing Sheets
